E. E. PETERSON,
ROCK DRILLING MACHINE,
APPLICATION FILED SEPT. 2, 1920.

1,379,283.

Patented May 24, 1921.

2 SHEETS—SHEET 2.

UNITED STATES PATENT OFFICE.

EWART ELIAS PETERSON, OF SEATTLE, WASHINGTON.

ROCK-DRILLING MACHINE.

1,379,283.

Specification of Letters Patent. Patented May 24, 1921.

Application filed September 2, 1920. Serial No. 407,663.

To all whom it may concern:

Be it known that I, EWART E. PETERSON, a citizen of the United States, and residing at Seattle, in the county of King and State 5 of Washington, have invented certain new and useful Improvements in Rock-Drilling Machines, of which the following is a specification.

This invention relates to an improved 10 portable apparatus designed particularly for use as a rock drill wherein provision is made for imparting the rapid series of blows to the drill and at the same time automatically turning the drill on its axis as is desirable in devices of this character.

The construction involves a gasoline or 15 similar engine having the crank shaft or driven shaft thereof provided with a cam member arranged to impart a series of 20 blows to a drill carrying spindle, the apparatus as a whole being utilized to maintain constant engagement between the cam and spindle. A spindle turning member is arranged to be given an intermittent movement 25 through the cam, so that during the impact or immediately following such impact, the spindle is given a partial rotation.

In the drawings:—

Figure 1 is a perspective view of the im- 30 proved apparatus.

Fig. 2 is an end elevation of the same.

Fig. 3 is a side elevation of the same.

The improved apparatus comprises a base 1 on which is mounted crank case 2 of a 35 single cylinder two-cycle engine, the cylinder of which is shown at 3. The crank shaft 4 of the engine is provided with a cam 5, the periphery of which is stepped at 6, to provide a material radial drop. The base 1 is 40 formed in line with the cam 5 with a sleeve 7 adapted to receive a spindle 8, the lower end of which is formed at 9 to receive a rock drill or other appropriate tool.

A shifting lever 10 is pivotally supported 45 on a projection 11 from the crank case 2, the pivot being formed of a removable bolt 12 threaded into the projection. The upper end of the lever 10 is provided with a roller 13 adapted to bear upon the periphery of 50 the cam 5, while the lower end of the lever is formed at 14 to engage any one of a series of elongated recesses 15 formed in the spindle 8. The wall of the sleeve bearing 7 is formed with an opening 16 to permit the 55 passage therethrough of the operative end of the shifting lever.

The crank case 2 is preferably provided with diametrically opposed handles 17 whereby the apparatus as a whole may be moved from place to place or supported by 60 an operator.

When in use as a rock drill, the weight of the apparatus as a whole causes the cam to bear upon the upper end of the spindle 8 so that at the rotation of the cam, which is 65 in the direction of the arrow, Fig. 1, a series of blows are imparted to the spindle as the cam offset rides by the spindle. Following each impact the shifting lever 10 is turned on its pivot 12 by the action of the cam to 70 thereby turn the spindle a distance equal to that between adjacent recesses.

The device is also adapted for use as a riveting machine, by substituting for the spindle 8, an appropriate riveting tool, and 75 removing the shifting lever by disconnecting its pivot. The impact due to the action heretofore described will successfully upset a rivet.

Claims:

1. An apparatus of the class described comprising a motor, a cam member operated thereby, an operating spindle arranged in line with the cam and maintained in contact with the cam through the weight of 85 the apparatus, the cam being formed to impart an impact to the spindle through such weight in each rotation of the cam.

2. An apparatus of the class described comprising a motor, a cam member operated thereby, an operating spindle arranged in line with the cam and maintained in contact with the cam through the weight of the apparatus, the cam being formed to impart an impact to the spindle through such 90 weight in each rotation of the cam, and means operated by the cam for turning the spindle.

3. An apparatus of the class described comprising a motor, a cam member operated thereby, an operating spindle arranged in line with the cam and maintained in contact with the cam through the weight of the apparatus, the cam being formed to impart an impact to the spindle through such 100 weight in each rotation of the cam, and a lever operated by the cam to engage and impart rotation to the spindle.

4. An apparatus of the class described comprising a motor, a cam driven thereby, a sleeve supported by the motor in line with the cam, a spindle mounted for free rotation 110

and longitudinal movement in the sleeve, and a lever pivotally supported on the motor and operated by the cam to impart a rotation to the spindle.

5. An apparatus of the class described comprising a base, a gasolene engine mounted thereon and having a crank shaft, a cam mounted on the crank shaft, a sleeve supported by the base in line with the cam, a

spindle mounted in the sleeve and having a 10 series of elongated recesses, and a lever pivotally supported by the engine and having one end to bear on the cam, and the opposite end to engage the recesses in the spindle, the movement of the lever by the cam 15 rotating the spindle.

In testimony whereof I affix my signature.
EWART ELIAS PETERSON.
